UNITED STATES PATENT OFFICE.

LEOPOLD STRASSER, OF NEW YORK, N. Y.

DESIGN FOR A WATCHCASE.

Application filed February 29, 1924. Serial No. 8,787. Term of patent 3½ years.

To all whom it may concern:

Be it known that I, LEOPOLD STRASSER, a citizen of the United States, residing at New York, in the county of New York, State of New York, have invented a new, original, and ornamental Design for a Watchcase, of which the following is a specification, reference being had to the accompanying drawing, forming part thereof.

The figure is a face view of a watchcase, showing my new design.

I claim:

The ornamental design for a watchcase, substantially as shown.

LEOPOLD STRASSER.
